UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

LAY-ROCK-SHAFT BEARING.

Application filed January 16, 1924. Serial No. 686,521.

To all whom it may concern:

Be it known that I, ALONZO E. RHOADES, a citizen of the United States, residing at Hopedale, in the county of Worcester and State of Massachusetts, have invented an Improvement in Lay-Rock-Shaft Bearings, of which the following description, in connection with the accompanying drawings, is a specification, like characters on the drawings representing like parts.

This invention relates to looms and more particularly to the lay rock-shaft bearings.

The constant rocking movement of the lay rock-shaft during weaving produces wear upon the bearing and lost motion between the operating parts which in time causes the path of the lay to assume a position different from its originally intended path and subjects the parts to play resulting in imperfect weaving.

Heretofore various expedients have been suggested for relieving the rock-shaft from wear, and the present invention relates to a construction in which the shaft supporting bearings do not come in actual contact with the rocking shaft so that the shaft itself is not subjected to wear.

The present invention is directed to a simple bearing construction which is inexpensive to manufacture and which may be readily adjusted from time to time to take up wear between the parts.

The invention will best be understood from the following description and accompanying drawings of one good practical form thereof.

In the drawings:—

Fig. 1 is a perspective view of the lower portion of the loom frame, showing a lay rock-shaft provided with the bearing of the present invention.

Fig. 2 is a sectional view through the lay rock-shaft and looking toward the bearing of Fig. 1.

Fig. 3 is a sectional view taken on the line 3—3 of Fig. 2.

Fig. 4 is a sectional view taken on the line 4—4 of Fig. 3; and

Fig. 5 is a vertical sectional view through the bearing.

The loom frame 1 may be of usual construction and comprises the usual side members having a web 2 provided with an enlarged opening 3 adapted to receive the bearing hub to be described, and the rock-

shaft 4 is provided with the lay swords 5 which may be of usual construction and are rigidly secured to the shaft 4.

It is obvious that should the lay rock-shaft 4 become badly worn it cannot be replaced readily, and the present invention therefore contemplates a bearing construction consisting of inexpensive parts that relieve the shaft from wear, and which may be readily adjusted to take up wear, or may be easily renewed without disassembling the loom.

In the construction shown the bearing consists of a hub 6 that projects into the opening 3 formed in the loom frame and the hub 6 preferably is provided with oppositely extending side or wing portions 7 and 8 which may be rigidly secured to the web 2 by bolts 9 passing through the wing portions and web, and the hub may be further secured in place by the pins 10. The hub 6 has a tapered bore adapted to receive a bushing 11 mounted upon the shaft 4 and having its outer surface tapered to fit the tapered bore of the hub. The bushing 11 is rigidly secured to the rock-shaft 4 by means to be described so that as the lay rocks back and forth the bushing 11 will rotate in the hub 6, and as the parts become worn the tapered bushing may be moved further into the hub to take up wear, or it may be rotated angularly to bring a different portion of the bushing below the shaft where the greatest wear occurs.

It is desirable to provide means for preventing the rock-shaft from moving in the direction of its length and also to secure the bushing 11 to the rock-shaft in the desired position of adjustment. To this end in the construction shown a collar 12 is provided mounted upon a protruding portion of the bushing 11 in position to abut against the outer end of the hub 6, and the collar 12 is rigidly secured to the shaft 4 in the desired position by a set screw 13 which extends through a clearance slot 14 in the bushing and engages the rock-shaft. The collar 12 is also preferably provided with a set screw 15 that rigidly secures the collar to the bushing.

As a result of this construction the bushing 11 may be moved to the desired position of adjustment within the hub 6, and then the collar 12 may be adjusted lengthwise of the rock-shaft 4 until its inner face rests

against the end of the hub 6. The parts may then be secured rigidly in this position by tightening the set screws 13 and 15.

The lower portion of the bearing will wear most rapidly as indicated at *a* in Fig. 5, due to the weight of the parts and the rocking movement of the lay shaft, and when it is desirable to make adjustment to compensate for wear, this may be readily done by simply loosening the set screw 13 so that the bushing 11 with the collar 12 rigidly secured thereto by the set-screw 15 may be rotated to bring a different portion of the bushing to the lowermost position. 15 Or if desired both set-screws 13 and 15 may be backed off and the tapered bushing 11 moved further into the hub 6 to take up the play. In this manner the bearings may be readily adjusted to take up wear without disturbing the various loom parts. 20

It will be understood that the opposite end portion of the rock-shaft 4 is supported by a bearing similar to that shown and described. The shoe 16 that supports the picker stick 17 may have a sleeve 18 as usual which is rigidly secured upon the projecting end of the rock-shaft by a set screw 19, and the inner end of the sleeve 18 may enter the recess 20 formed within the collar 12. Oil may be supplied to the bearing through the oil holes 21 and 22.

What is claimed is:—

1. A bearing for the lay rock-shaft of a loom, comprising a bearing hub rigidly secured to the loom frame and having a tapered bore, a bushing fitted upon the lay rock-shaft and having its outer surface tapered to fit and rotate in the tapered bore of said hub and constructed for adjustment both angularly and longitudinally within the hub to take up wear, a separate collar mounted upon the bushing for adjustment independent of the bushing to limit movement of the rock-shaft in the direction of its

length, means for securing the collar rigidly to the bushing, and separate means for securing the bushing rigidly to the shaft in any angularly or longitudinally adjusted position. 45

2. A bearing for the lay rock-shaft of a loom, comprising a bearing hub rigidly secured to the loom frame and having a tapered bore, a bushing fitted upon the lay rock-shaft and having its outer surface tapered to fit and rotate in the tapered bore of the hub and constructed for adjustment both angularly and longitudinally within the hub to take up wear, a separate collar mounted upon the bushing for adjustment independent of the bushing to limit movement of the rock-shaft in the direction of its length, and means for securing the bushing and collar rigidly to the shaft in different positions of angular and longitudinal adjustment. 50 55 60 65

3. In a lay rock-shaft bearing for looms, the combination of a bearing hub secured to the loom frame and having a tapered bore, a bushing fitted upon the lay rock-shaft and having its outer surface tapered to fit the tapered bore of the hub and provided with a slot extending longitudinally of the bushing, a collar separate from the bushing and mounted on the outer end thereof, a set screw extending through the collar and the longitudinally extending slot of the bushing and adapted to bear upon the lay rock shaft to clamp the collar and hub to the lay rock-shaft for rocking movement therewith while permitting longitudinal adjustment of the bushing on the rock-shaft relative to the collar and bearing against the bushing to permit adjustment of the collar relative to the bushing. 70 75 80

In testimony whereof, I have signed my name to this specification. 85

ALONZO E. RHOADES.
